ATTORNEY.

UNITED STATES PATENT OFFICE

LEWIS MONTFORD McCORMICK, OF PALO ALTO, CALIFORNIA

SUCTION LIFTING DEVICE

Application filed November 2, 1927. Serial No. 230,523.

This invention relates to improvements in suction lifting devices of the kind adapted to draw fluids into containers.

An object of my invention is to provide an improved suction lifting device having a construction adapted to draw liquids into pipettes with fine precision and accuracy.

A further object of my invention is to provide an improved suction lifting device which 10 may be operated to draw liquids into pipettes without any danger of contamination or infection accompanying its use.

A further object of my invention is to provide an improved instrument for drawing 15 specific quantities of liquid into containers.

The devices now commonly used to fill pipettes, which are operated by inserting the end of a tube into the mouth, are apt to become contaminated through their contact 20 with objects or substances not previously sterilized. By means of the present invention the danger of contamination or infection accompanying the use of pipette fillers is practically eliminated, principally because 25 the instrument is not inserted into the mouth of the operator when used.

Other advantages and objects of the present invention will present themselves or will be specifically pointed out in the description to follow.

In the accompanying drawings:

Fig. 1 is a side view of a liquid suction device embodying my invention;

Fig. 2 is a longitudinal sectional view of the 35 same taken on the line 2—2 of Fig. 1;

Fig. 3 is a longitudinal sectional view of a fragmentary part of a modified form of liquid suction device embodying my invention;

Fig. 4 is a longitudinal sectional view of the 40 fragmentary part of another modified form of liquid suction device embodying my invention showing a means which may be employed with the two plungers for preventing the suction of air through the barrel of the device.

Referring to Figs. 1 and 2 of the drawings, the numeral 1 designates a hollow cylindrical shaped barrel having a longitudinally extending slot 2 located in its side, and suitable

threads at its ends for the attachment of a cap 3 and a nozzle 4.

Movably located inside the barrel 1 is a closely fitting plunger 5 having a small opening 6 extending longitudinally therethrough 55 which registers with the opening located in the said nozzle. Movably located inside the opening 6 is a small closely fitting plunger 7 which is adapted to be moved independently of the larger plunger 5. 60

Secured to the side of the large plunger 5 at a point adjacent its end, is a finger piece 8 which projects through the slot 2 and serves as a means for conveniently moving the said large plunger backwardly and forwardly inside the barrel 1. 65

The small plunger 7 is secured at its end to a disc member 9 which movably fits within the barrel, and the said disc member is provided with a finger piece 10 which projects through the slot 2 and serves as a means for moving the said small plunger backwardly and forwardly within the small opening 6. 70

As shown in Fig. 4, the plunger 5 may be provided with an encircling band 11, composed of rubber or other suitable material, the said band being adapted to firmly fit against the side of the barrel to prevent the possible suction of air between the walls of the barrel and the circumferential surface of the said 80 plunger. Located adjacent an end of the plunger 5, inside an enlargement of the small opening 6 and around the small plunger 7, is suitable packing material 12 which may be pressed against the small plunger by a screw 85 13. The screw 13 may be screwed into suitable threads provided in the large plunger for that purpose, to press the packing material 12 firmly against the small plunger 7 and the walls of the enlarged part of opening 6, and thereby prevent the suction of air through the 90 said small opening.

As shown in Fig. 3, my invention may be embodied in another form in which the two plungers are positioned in the barrel but apart 95 from each other. In this figure the barrel 1 is shown as having the nozzle 4 integrally formed therewith, with a longitudinally extending enlargement 14 located on the inside of the said barrel at a side thereof. The en- 100

largement extends part way along the side of the barrel and is provided with a small longitudinally extending opening 15 within which the small plunger 7 movably fits. A large 5 plunger 5 movably contacts with a side of the barrel and the inside surface of the enlargement 14, and the end thereof is provided with a disc 16 which contacts with the walls of the said barrel. Attached to the disc 16 is a finger- 10 piece 8 which projects through the slot 2 in the said barrel. The disc 9 attached to the small plunger 7 and provided with the finger piece 10, serves as a means for moving the said plunger backwardly and forwardly in the 15 opening 15.

The device herein shown and described is particularly adapted for use in filling pipettes with desired quantities of liquids. As illustrated in Figs. 1 and 2, the nozzle 4 is inserted 20 in the end of a pipette 17 in the usual manner, with the end of the pipette contacting with a particular kind of liquid to be drawn therein. The finger piece 10 is moved by a finger toward the end of the barrel, thereby carrying 25 with it the small plunger 7. A partial vacuum is thereby created in the pipette and in the nozzle and a fine stream of the liquid is drawn into the pipette to the desired level. After the desired amount of this liquid has been 30 thus drawn into the pipette, the latter is placed in contact with another body of liquid, and the finger piece 8 is moved toward the end of the barrel, thereby carrying with it the larger plunger 5. As the larger plunger 5 is 35 thus moved away from the nozzle 4, a larger stream of fluid is drawn into the pipette, thereby quickly completing the operation of filling the same with the desirable proportions of liquids to be treated or analyzed.

40 It is apparent to those skilled in the art that my improved suction device may be embodied in forms other than those herein shown, so for this and other apparent reasons I desire my invention included broadly within the spirit 45 of the appended claims.

Having described my invention, what I claim is:

1. A device of the class described comprising a barrel having a slot therein, a plunger 50 movably located in the barrel and provided with an opening extending therethrough, a second plunger movably located in the opening in the first mentioned plunger, and separate finger pieces extending through the slot 55 in the barrel and attached to the said plungers, whereby the said plungers may be moved independently of each other.

2. In a device of the class described, the combination comprising a hollow barrel, a 60 large plunger movably located in the barrel, a small plunger movably located in the barrel, separate means for moving the plungers, whereby either plunger may be actuated to create a vacuum in the barrel, and means for 65 preventing the plungers from turning.

3. A device of the class described comprising a hollow barrel, a plunger slidably located in the barrel having an opening therethrough, a second plunger slidably located in the opening in the first mentioned plunger, separate 70 means associated with each plunger, whereby each plunger may be actuated independently of the other, and means for preventing the plungers from turning.

4. A device of the class described comprising a hollow barrel, a plunger slidably located in the barrel for producing a partial vacuum in the barrel, the said plunger having an opening therethrough, a second plunger movably located in the opening in the first mentioned 75 plunger for also producing a partial vacuum in the barrel, means associated with each plunger, whereby each plunger may be actuated independently of the other, and means for preventing the plungers from turning.

5. A device of the class described comprising a barrel having a slot in its side, a plurality of plungers movably located in the barrel, and a separate finger piece associated with each plunger and extending through the slot 90 in the barrel for actuating the plungers.
